HARDENING PRINTED INK FILMS

Alfred F. Schmutzler, Teaneck, N. J.

Application April 4, 1945, Serial No. 586,548

1 Claim. (Cl. 101—416)

1

This invention relates to the drying of steam-setting printing inks.

Steam-setting printing inks usually comprise a coloring material homogeneously suspended in a lacquer-like composition, in which the solvent is a liquid polyhydric alcohol. They may be used on the usual commercial printing presses, and their printed films can be dried by exposure to steam.

The hardening or drying of these ink films is a precipitation phenomenon. The steam, usually issuing from a row of jets, saturates the atmosphere with moisture, while the water soluble solvent absorbs sufficient water to cause the separation of the binder. During this precipitation, the coloring material adheres to the binder. In this process of hardening printing ink films, the drying proceeds in one direction, e. g. from the outer layer toward the paper.

This steam-setting method was developed due to the disadvantages encountered with a somewhat older quick drying process relying upon the direct heat from gas burners. The latter treatment dries out the paper and usually causes it to shrink. The steam treatment eliminates this defect; it has met with great success in printing processes other than that with high speed rotary presses as of the type shown in Gessler U. S. Patent 2,317,372 of April 27, 1943. Apparently the shorter exposure of the printed ink films on the speeding web is not sufficient to dry the ink. Longer exposures to steam by multiplying the number of rows of steam jets is not always effective. Especially at low atmospheric humidity, it seems that a layer, impermeable to steam, surrounds the speeding web; and in such a layer the humidity is not substantially raised to cause the hardening of the printed ink films.

I have found that by raising the moisture content of the paper prior to printing, the printed films from steam-setting printing inks harden more quickly during subsequent exposure to heat or steam. This procedure will facilitate the drying of steam-setting printing ink films on rotary high speed presses.

The paper or the web may be moistened by a fine spray of water, such as from an atomizer, or a jet of steam, or the moistening of the paper may be accomplished by a system of printing press rollers. Since paper has the capacity to hold widely varying percentages of water, control of wetting is necessary but not critical; relatively large proportions of water above the normal moisture content of paper may be applied without effecting proper printing operations.

2

If the paper is moistened by a system of printing press rollers during the operation of a high speed rotary printing press, the water has little chance to penetrate deeply into the web before the printing takes place. Thus the moisture will be at the outermost layer where it is needed for its task. Furthermore, if the paper is exposed to the direct heat of impinging flames, its tendency to shrink is considerably reduced. Whether the final hardening of the printed film will be accomplished by direct heat or by the exposure to steam, either method combined with moistening the paper prior to printing effects the hardening of the ink film from both sides.

10 The application of this invention may be illustrated by the following examples:

Example I

Figure 1 schematically presents the path of a web of fibrous material through the printing process on a rotary press. As the web of fibrous material unwinds from roller E, its surface is wetted by the moistening roller D, which may also serve as the tension roller. The water supplied comes from the fountain A, in which roller B is thoroughly wetted; distributing roller C is wetted by roller B, and it transfers the water to the moistening roller D. It is understood that the set of rollers require an elaborate arrangement for adjusting the rollers; they may be adjusted so that they do not touch each other or may be adjusted so that they would squeeze each other. Any intermediate adjustment controls the amount of water transferred to the surface of the web on its path to the printing mechanism. Though the hardening of the printed ink film is independent of the printing mechanism, Figure 1 illustrates a usual arrangement, such as an ink fountain F, from which the ink is picked up by roller G; distributing roller H shears the ink off roller G, and transfers it to the impression roller I, which inks the web while it is passing over the roller K. After printing, the moisture in the surface of the paper aids the impinging steam, issuing from the orifices of a row of steam pipes L, in hardening the printed ink films.

Since sufficient moisture is already available in the surface of the fibrous material, steam is really not necessary to cause the hardening of steam-setting printing inks; some other form of heat, such as from an electric heating element, or from gas burners or oil burners, will just as well accomplish the hardening of the ink film.

55 After the ink film is hardened, it is customary

to rewind the web, after passing over roller M, or pass it over a direction-reversal roller N for printing the back of the fibrous material. In the latter case, the same arrangement for wetting can be made prior to printing.

Example II

In order to moisten the web of fibrous material shortly before printing, rows of steam jets may be placed around the unwinding roller E and along the path of the web ahead of the printing mechanism, as illustrated in Figure 2, which indicates the usual path of the web of fibrous material on a rotary printing press, as explained in Example 1. Steam pipes with tiny orifices are arranged in rows A, B, C and D so that the orifices face the web. As the roller E unwinds and the web travels toward the printing mechanism, all or part of the steam pipes can be brought into operation to wet the surface of the fibrous material for proper printing operation. The number of pipes in operation will depend upon the speed of the press and the pressure of the steam. After the printing, the moisture in the surface of the paper aids the impinging steam, issuing from the orifices of a row of steam pipes L, in hardening the printed ink films.

In place of steam pipes for moistening the web of fibrous material prior to printing, water pipes with atomizers can be installed.

Example III

The unwinding web is cooled below room temperature by either exposing it to liquid air, solid carbon dioxide (Dry Ice) or by passing it over several supercooled rollers, then a spray of steam or a spray of atomized hot water is impinged upon the paper in order to moisten and reheat the paper, as closely to room temperature as desired, prior to printing. After printing one of the several methods of drying may be applied.

It is understood that the afore-mentioned examples are to serve as a guide and that changes may be made without departing from the scope

of this invention, as described and defined in the appended claim.

What is claimed is:

5 A method of improving the speed of hardening of a printed water sensitive ink film printed by a high speed rotary press on a rapidly moving web of fibrous material, which comprises moistening the surface of said fibrous material immediately prior to printing with ink comprising a coloring material, a water insoluble binder and a water miscible solvent, forthwith printing said web while a substantial portion of the moisture is at said surface, and immediately after printing, causing the evaporation of excess moisture at 10 the surface of the unprinted portion of the web to make it available for the thorough hardening of said ink film.
